UNITED STATES PATENT OFFICE

CHARLES W. FAILOR, OF FOREST HILLS BOROUGH, PENNSYLVANIA, ASSIGNOR TO THE UNION SWITCH & SIGNAL COMPANY, OF SWISSEVALE, PENNSYLVANIA, A CORPORATION OF PENNSYLVANIA

RAILWAY TRAFFIC CONTROLLING APPARATUS

Application filed February 18, 1930. Serial No. 429,290.

My invention relates to railway traffic controlling apparatus, and particularly to apparatus of the type involving coded track circuits for the control of signals, which 5 may be either wayside signals or train-carried signals or both.

I will describe one form of apparatus embodying my invention, and will then point out the novel features thereof in 10 claims.

In the accompanying drawings, Figs. 1^a and 1^b, when placed end to end with Fig. 1^a on the left, constitute a diagrammatic view showing one form of apparatus embodying 15 my invention.

Referring to the drawings, the reference characters 1 and 1^a designate the track rails of a stretch of railway track along which traffic normally moves in the direction indicated by the arrow. These rails are divided by insulated joints 2 to form a plurality of sections U—V, V—W, etc.

The energy for the operation of the apparatus is furnished by transformers L, one 25 of which is located at each junction of adjacent sections. The primary 6 of each of these transformers is connected with a transmission line E which is constantly supplied with alternating current of a suitable com- 30 mercial frequency, such as 60 cycles per second, from a source which is not shown in the drawings. An auxiliary transformer M is located at each junction of adjacent sections, and its primary 7 is connected with 35 secondary 5 of the associated transformer L.

One secondary 9 on each transformer M furnishes current for the operation of the wayside signals which are hereinafter described, and another secondary 8 on each of these 40 transformers is connected with the input terminals of a rectifier 10 which furnishes direct current for the operation of certain parts of the apparatus.

Each track section is provided with a 45 track relay T, having a track winding 3 con-

nected across the rails at the entrance end of the section, and a second winding 4 constantly supplied with alternating current from the secondary 5 of the associated transformer L. Each track section is also provided with a track transformer C, the secondary 35 of which is connected across the rails at the exit end of the section through the usual current-limiting impedance 37. As explained hereinafter in detail, the primary 36 of each track transformer is supplied with alternating current from the associated transformer L, which current is periodically interrupted or coded at the rate of 80 cycles per minute, 120 cycles per minute, or 180 cycles per minute, and so it follows that when any given track section is unoccupied, the track relay T for such section is operating at the rate of 80, 120 or 180 cycles per minute.

Each track relay T controls decoding apparatus involving three relays H, D and DD, in such manner that these relays are selectively responsive to operation of the track relay at the three rates specified. This apparatus comprises a transformer F, the primary 11 of which is supplied with direct current from the associated rectifier 10 through a contact 13 of relay T. When the relay T is energized, current flows from the upper terminal of rectifier 10 to the front point of contact 13, then through the right-hand half of primary 11 to the lower terminal of rectifier 10. When relay T is de-energized, current flows through the left-hand half of primary 11 and the back point of contact 13. It follows that while track relay T is operating, an alternating voltage is induced in the secondary 12 of transformer F, the frequency of which is the same as the frequency of operation of the associated track relay T. A condenser 14 may be connected across the primary 11 to prevent undue sparking at contact 13. The transformer F is provided with a first sec-

ondary circuit, which includes a reactor 34^H and a rectifier 15^H connected in series, and the output terminals of this rectifier are connected with decoding relay H. The parts of this circuit are so proportioned and adjusted that relay H will respond to any one of the three codes. Transformer F is provided with a second secondary circuit which includes a reactor 34^D in series with which are two condensers 16 and 17 connected in multiple. The input terminals of a rectifier 15^D are connected across a portion of the rectifier 34^D, and the output terminals of this rectifier are connected with the decoding relay D. The parts of this circuit are so proportioned that relay D responds only to the code of 120 cycles per minute. A third secondary circuit for transformer F includes a reactor 34^{DD} and a condenser 18 connected in series. A rectifier 15^{DD} has its input terminals connected with a portion of the reactor 34^{DD}, and the output terminals of this rectifier are connected with the decoding relay DD. The parts of this circuit are so proportioned that relay DD responds only to the code of 180 cycles per minute.

Each section is provided with a coding device K comprising a motor 38 constantly connected with the secondary 5 of the associated transformer L, and three contacts 26, 27 and 28, which are periodically closed at 180 cycles per minute, 120 cycles per minute, and 80 cycles per minute, respectively. The primary 36 of each track transformer C is supplied with coded current through one or another of these contacts according to the conditions of the decoding relays for the section next in advance.

Each section is provided with a wayside signal S, comprising two groups of lamps A and B. Group A comprises a green lamp G, a yellow lamp Y, and a red lamp R. Group B comprises a green lamp G and a red lamp R. The lamps of each signal are controlled by the decoding relays H, D and DD for the corresponding section in a manner which will be explained hereinafter in describing the operation of the apparatus.

As shown in the drawing, section X-Y is occupied by a train Z, so that track relay T^X is continuously deenergized. It follows that there is no alternating voltage in the secondary of transformer F^X, so that all three of the decoding relays H, D and DD, associated with this transformer, are deenergized. The circuit for the primary winding 36 of transformer C^X then passes from the right-hand terminal of secondary 5 of transformer L^X, through primary 36, back point of contact 21 of relay H, contact 28 of coding device K^X, to the left-hand terminal of secondary 5. It follows that alternating current periodically interrupted at the rate of 80 cycles per minute is being supplied to the track rails of section W-X,

so that track relay T^W is operating at the rate of 80 cycles per minute. As for signal S^X, the red lamp R of group A is lighted by virtue of a circuit which passes from secondary 9 of transformer M^X, through the back point of contact 20 of relay H, wire 33 and lamp R to secondary 9. Lamp R in group B of signal S^X is also lighted by virtue of a circuit which passes from secondary 9, through the back point of contact 19 of relay H, wire 32, and lamp R to secondary 9. It follows that signal S^X indicates "stop".

Inasmuch as track relay T^W is operating at 80 cycles per minute, decoding relay H is controlled by this relay is energized, whereas the other decoding relays D and DD are both deenergized. Lamp Y of signal S^W is lighted by virtue of a circuit which passes from secondary 9 of transformer M^W, through the front point of contact 20 of relay H, back point of contact 24 of relay DD, wire 30, and lamp Y to secondary 9. Lamp R of group B is also lighted by virtue of a circuit which passes from secondary 9, through the front point of contact 19 of relay H, back point of contact 22 of relay D, wire 32, and lamp R to secondary 9. It follows that signal S^W indicates to an approaching train that section W-X is unoccupied but that section X-Y is occupied. The circuit for the primary 36 of track transformer C^W is from secondary 5 of transformer L^W, through primary 36, front point of contact 21 of relay H, back point of contact 23 of relay D, back point of contact 25 of relay DD, and the 120 cycle contact 27 of coding device K^W to secondary 5. It follows that alternating current periodically interrupted at the rate of 120 cycles per minute is being supplied to the track rails for section V-W.

Inasmuch as track relay T^V is operating at the rate of 120 cycles per minute, relays H and D associated with this track relay are both energized, whereas the associated relay DD is deenergized. Lamp Y of signal S^V is therefore lighted by a circuit which passes from secondary 9 of transformer M^V, through the front point of contact 20 of relay H, back point of contact 24 of relay DD, wire 30, and lamp Y to secondary 9. Lamp G in group B is also lighted by a circuit which passes from secondary 9, through the front point of contact 19 of relay H, front point of contact 22 of relay D, wire 31, and lamp G to secondary 9. Signal S^V therefore indicates to an approaching train that sections V-W and W-X are unoccupied but that section X-Y is occupied. The circuit for the primary 36 of track transformer C^V is from secondary 5 of transformer L^V, through primary 36, front point of contact 21 of relay H, front point of contact 23 of relay D,

and the 180 cycle contact of coding device K^U to secondary 5. It follows that alternating current periodically interrupted at the rate of 180 cycles per minute is being supplied to the rails of section U—V.

Inasmuch as track relay T^U is operating at the rate of 180 cycles per minute, relays H and DD associated with this track relay are energized, but the associated relay D is deenergized. Lamp G in group A of signal S^U is therefore lighted by virtue of a circuit which passes from secondary 9 of transformer M^U , through the front point of contact 20 of relay H, front point of contact 24 of relay DD, wire 29, and lamp G to secondary 9. Lamp R in group B of this signal is also lighted, the circuit being from secondary 9, through front point of contact 19 of relay H, back point of contact 22 of relay D, wire 32, and lamp R to secondary 9. Signal S^U therefore indicates to an approaching train that sections U—V, V—W and W—X are all unoccupied. The track rails for the section to the left of point U are being supplied with alternating current periodically interrupted at 180 cycles per minute, the circuit being from the secondary 5 of transformer L^U , through primary 36 of transformer C^U , front point of contact 21 of relay H, back point of contact 23 of relay D, front point of contact 25 of relay DD, and the 180 cycle contact 26 of coding device K^U to secondary 5.

It will be obvious from the forgoing, that the trackway apparatus shown in the drawings may be used for the control of train-carried apparatus receiving current inductively from the track rails, such for example as the apparatus disclosed and claimed in application for Letters Patent of the United States filed by P. N. Bossart on the 7th day of February, 1927, Serial No. 166,407. In this event, the indications given by the train-carried apparatus will be the same as those given by the trackway signals, and so it follows that the trackway apparatus illustrated in the present application may be used for the control of wayside signals or train-carried signals or both.

One important feature of my invention is that coded energy for operation of the wayside signal in any one section, or for the operation of the signal on a train in such one section, is dependent on coded track circuit energy in sections in advance, and consequently false clear signals due to foreign current are impossible because such current will not have the code characteristics required for the operation of the decoding relays.

Other features and advantages are as follows: The coded track circuits make it possible to provide a safe and efficient "three-block" indication system without the necessity for line wires. The same energy that is

used for the operation of the wayside signals may be used for the operation of train-carried signals. A separate source of track circuit energy, which has been required in code train control systems, is rendered unnecessary because coded current is used for track relay operation. All problems relating to inductive and capacity interference in line wires are eliminated. No approach control is involved, and consequently all problems relating to the reset of approach control apparatus are eliminated. Decoding equipment of the same kind may be used for both train and wayside signals, thus permitting standardization of apparatus with consequent reduction of cost. The system is universal, in that it may be applied to railroads on which the motive power is steam, alternating current or direct current.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, a stretch of railway track divided into sections, a track relay and three decoding relays H, D and DD for each section; means controlled by the decoding relays for each section for supplying the rails of the section next in the rear with alternating current periodically interrupted at one rate when relay H is deenergized, at a second rate when relay H is energized and relays D and DD are deenergized, and at a third rate when relay H and either relay D or DD are energized; each track relay being responsive to the periodic interruptions of the alternating current thus supplied to the rails of its section; means controlled by each track relay for energizing the associated relay H in response to alternating current periodically interrupted at the first rate, relays H and D in response to alternating current periodically interrupted at the second rate, and relays H and DD in response to alternating current periodically interrupted at the third rate; and signals for the sections controlled by said decoding relays.

2. In combination, a stretch of railway track divided into sections, a track relay and three decoding relays H, D and DD for each section; means controlled by the decoding relays for each section for supplying the rails of the section next in the rear with alternating current of commercial frequency periodically interrupted at the rate of 80 cycles per minute when relay H is deenergized, 120 cycles per minute when relay H is energized and both relays H and DD are deenergized, and 180 cycles per minute when

relay H and either relay D or DD are energized; each track relay being responsive to the periodic interruptions of the alternating current thus supplied to the rails of its section; means controlled by each track relay for energizing the associated relay H when operated 80 times per minute, relays H and D when operated 120 times per minute, and relays H and DD when operated 180 times per minute; and signals for the sections controlled by said decoding relays.

In testimony whereof I affix my signature.

CHARLES W. FAILOR.
